UNITED STATES PATENT OFFICE.

OTIS E. DINGLEY, OF WEST FARMINGTON, MAINE.

DEMOUNTABLE RIM.

Application filed May 10, 1921. Serial No. 468,286.

To all whom it may concern:

Be it known that I, OTIS E. DINGLEY, a citizen of the United States of America, and resident of West Farmington, in the county of Franklin and State of Maine, have invented new and useful Improvements in Demountable Rims, of which the following is a specification.

This invention concerns demountable rims for vehicle wheels and relates more particularly to means for connecting the rim to the felly of the wheel. Connecting means of the general character to which this invention appertains is disclosed in the patent to 10 Dingley, No. 1,205,866, November 21, 1916. In the patented device, the rim retaining bolts, which are carried by the felly, are provided with substantially cylindrical ends engageable with sockets of similar 15 form in the rim. While very effective for the desired purpose, a considerable degree of care is necessary in the preliminary positioning of the parts in order to ensure the entrance of the bolt ends into their respective 20 sockets, with which they are made closely to interfit.

The principal object of the present invention is to so improve the device of the above noted patent and particularly the cooperating 25 portions of the attaching bolts and their sockets as to facilitate the engagement of the bolts with their sockets, even though in the initial position of the parts the bolts and their respective sockets be somewhat 30 out of alignment or eccentric one to the other. The contemplated improvement has the further advantage, that even though the socket be obstructed, as for example, by the formation of burrs about its edges or by the 35 presence of mud or other foreign material therein, the proper and certain entrance of the bolt is substantially assured.

As a preferred embodiment of means for carrying into effect the above object, that 40 disclosed in the accompanying drawings may be employed, and in which,

Fig. 1 is a side elevation illustrating a vehicle wheel embodying the present invention;

Fig. 2 is a cross section, to enlarged scale, showing the present invention as applied to the attaching of the demountable rim to the wheel felly;

Fig. 3 is a fragmentary cross section 50 showing a modification of the device of Fig. 2;

Fig. 4 is a view similar to Fig. 3 illustrating a further modification; and

Fig. 5 is a fragmentary plan view of the outer side of the felly illustrating an arrangement employed at one point thereon.

Referring to the drawings there is indicated in Fig. 2 a wheel of usual form comprising a hub 1, spokes 2, and a felly 3, such felly having mounted thereon the demountable rim 4 carrying the tire 5.

The demountable rim 4 is indicated as provided with an opening at 6 (Fig. 2) such opening being one of a series of openings spaced apart about the periphery of the rim and preferably so arranged as to come opposite the spaces between every other pair of spokes 2 of the wheel. Within the openings 6 are seated disk members 7 preferably provided with radial flanges 8 which overlap the inner surface of the rim. While in accordance with the present disclosure, these disk members are made independent of the rim and seated therein, being formed of a harder and more wear-resistant material than that of the rim, it is contemplated that they may, if desired, be formed as integral portions of the rim, as clearly disclosed in the patent above referred to. These disk members provide thickened portions or bosses having therein radially disposed socket openings 9. As disclosed in Fig. 2, such socket openings are of substantially conical form, tapering to a point at their inner ends.

The felly 3 is provided with a series of metallic sleeves 10, corresponding in number to the disk members 7 in the rim, and arranged to align therewith. The sleeves 10 may, if desired, be provided with flange portions 8 which, in operative position, lie flush with the outer surface of the felly, the sleeves being forced into openings in the felly and being provided, if desired, with fins such as indicated in the above noted patent, whereby to prevent rotation of the sleeves within their respective openings. The sleeves 10 are provided with internal screw threads 12 of relatively coarse pitch, and engageable with such screw threads are threads 14 carried by the central portions of attaching bolts 13. In accordance with the preferred arrangement, the bolts 13 at their inner ends, that is to say, the ends which normally extend toward the hub of the wheel, are somewhat reduced in diameter and provided with screw threads 15 of finer

pitch, with which latter threads engage lock nuts such as 16. The inner ends of the bolts 13 are preferably formed with square heads, or in any other desired manner permitting ready application of a tool thereto, for rotatably adjusting the bolt. At their outer portions, the bolts 13 are formed with tapered ends, such ends being indicated in Fig. 2 as of conical form, thus providing surfaces engageable with the conical sockets 9.

The rim and felly, at corresponding points therein, are provided with suitable openings for the passage of the usual tire valve 21, and at a point substantially opposite such openings, the outer surface of the felly may be provided with a rib 22, substantially of U form, encircling the threaded opening in one of the sleeves 10, such rib serving to guide the corresponding flange 8 into proper alignment with the threaded opening in the sleeve 10 as the rim is slipped over the felly.

In the operation of the parts above described, the rim having been placed over the felly, the several bolts 13 are rotated by means of their angular heads, thereby causing them to move radially outward and bringing their tapering end portions into engagement with the corresponding sockets 9. By reason of the provision of the tapering end upon the bolt 13, it is evident that, even though the socket and bolt be not accurately aligned at the beginning of the operation, the engagement of the inclined surface of the bolt with any portion of the socket opening serves automatically, upon tightening of the bolt, to bring the parts into alignment. Furthermore, if for any reason the socket be obstructed, as by the presence of mud or other foreign matter therein, the conical end of the bolt will serve to push aside and squeeze out such material, rather than to compress the same into the bottom of the socket, and thus little care is necessary on the part of the operator in ensuring a proper seating of the bolts within their respective sockets. Upon completion of the adjustment of the bolts, they may be positively locked in position by tightening the lock nuts 16, thereby holding the parts securely in proper position.

In the arrangement shown in Fig. 3, the rim is indicated at 4^a having the disk members 7^a seated therein. The felly is indicated at 3^a, having the internally threaded sleeve 10^a secured therein, such sleeve having the threaded bolt 13^a positioned within it. The members 7^a, in this instance, however, is provided with a substantially cylindrical socket 23, the bottom wall of which is inclined to the axis thereof, thus providing an end portion of substantially conical

form as shown at 9^a. The cylindrical end portion of the bolt, indicated at 24, engages 65 within the cylindrical portion 23, while the conical end 18^a of the bolt seats against the conical bottom wall of the socket. This arrangement secures all the advantages of that previously described, but, in addition, 70 affords engaging surfaces of somewhat greater extent.

In the device illustrated in Fig. 4, the rim 4^b is shown as having the disk member 7^b seated therein and the felly 3^b as having the 75 threaded sleeve 10^b secured therein. The threaded bolt 3^b is also shown as engaging the sleeve 10^b. In this case, the socket in the member 7^b has a cylindrical portion 27 and at its inner extremity has a face 25 substantially perpendicular to its axis. Connecting the face 25 and the cylindrical wall 27 is a beveled or inclined surface 26. The end of the bolt 13^b also has a cylindrical portion 28 engaging the cylindrical part 27 of the socket and terminates in a square end engaging the face 25. Interposed between such flat face and the cylindrical portion of the bolt is a bevel face 29 engageable with the surface 26.

It will be noted with respect to all of the several described forms, that the end of the bolt which engages the socket is provided with a guiding surface inclined to its axis, such guiding surface serving, as the parts are brought into engagement, automatically to bring them into axial alignment. While either of the forms thus described may be employed in producing the desired result, that indicated in Fig. 3 is regarded as the 100 preferred form wherein all the advantages of the conical end are secured while at the same time an increased area of contact between the bolt and its socket is provided.

Having thus described the invention in a preferred embodiment of the same, what I claim and desire to secure by Letters Patent of the United States is:

In combination with a wheel felly and a detachable rim, said rim having a plurality 110 of spaced members secured in spaced openings therein, said members being flush with the outer surface of the rim and having inwardly directed, unobstructed conical socket openings, a plurality of bolts having external screw threads of coarse pitch engaging threaded openings in the felly, said bolts having conical, solid heads for engagement with the respective socket openings, said bolts at their outer ends having screw threads of relatively fine pitch, and locking nuts engaging the last named threads whereby to secure the bolts in adjusted position.

Signed by me at Boston, Massachusetts, this 7th day of May, 1921.

OTIS E. DINGLEY.
